ELECTRICAL MUSICAL INSTRUMENT OF
THE TYPE EMPLOYING GASEOUS DIS-
CHARGE TUBESWinston E. Kock, Cincinnati, Ohio, assignor to
The Baldwin Company, Cincinnati, Ohio

Application December 11, 1935, Serial No. 53,955

8 Claims. (Cl. 84—1)

This invention relates to an electrical musical instrument of the type employing gaseous discharge tubes.

In instruments previously devised employing the ordinary glow tube oscillators, difficulty has been experienced in obtaining sufficient stability of pitch, due to the fact that changes in the characteristics of the glow lamps affect the frequency of the electrical oscillations generated.

10 Several methods overcome this to a certain extent. For example the insertion of an inductance in the condenser circuit in order to obtain an "inductive glow discharge oscillator", as described in my United States Patent No. 2,046,463, issued

15 July 7, 1936, from an application Serial No. 701,173, copending with this application, will materially reduce the instability. However, this procedure requires an inductance for each note of the scale, which introduces weight and expense in an organ, where 73 to 85 such oscillators may be required.

Another method is to provide coupling between those oscillators which are at octave separation, since such oscillators have frequencies which are 25 harmonically related, and coupling means would cause them to lock into step with one another. For the ordinary glow discharge oscillator (the relaxation oscillator) this procedure is of no value because of the fact that in order to obtain 30 sufficiently tight coupling to hold the various octaves in step even to within a semitone or so, a voltage from the other oscillators must be used which would introduce objectionable harmonics and subharmonics into the outputs of the individual generators. Coupling between oscillators of the inductive glow discharge type is more effective in this respect, due to the fact that their 35 control circuits (inductance and capacity) resonate at the frequency of their corresponding oscillators and the undesirable harmonic and subharmonic components are automatically filtered out.

It is an object of this application to describe a novel coupling means which dispenses with inductances for all but one octave, and completely eliminates the undesirable presence of sub- or super-harmonics in the output of the generators.

In this method, use is made of the control action of the grid electrode of a three-electrode discharge tube. If a three-electrode tube, operating as a relaxation oscillator, has a certain frequency of oscillation with fixed grid bias, the introduction into the grid circuit of a small alternating voltage of a frequency 50% or even 100% greater than this original frequency will cause the dis-

charge tube to oscillate at the frequency of this impressed grid voltage. Furthermore, frequencies at octave separation are easily obtained.

In the drawing Fig. 1 is a main oscillator and one an octave below.

Fig. 2 shows part of the circuit of an electrical musical instrument, including the circuit of Fig. 1.

Fig. 3 shows a filter circuit.

In Figure 1 oscillator O_2 is oscillating at say 10 400 cycles, so that a 400 cycle voltage appears across R_2 . With switch S_1 open, oscillator O_3 is oscillating at say 150 cycles. When switch S is closed and the alternating voltage on R_2 is impressed on the grid of O_3 , the oscillator O_3 will 15 lock into step at 200 cycles, so that O_2 and O_3 will be at octave separation. This procedure can be cascaded to obtain oscillators oscillating at 20 100 cycles, 50 cycles, etc. so that the entire bank of oscillators are at octave separation.

It is to be noted that a tendency for O_3 to shift in pitch is not transferred to O_2 . For example, a change in the condenser C_2 will effect no change in the frequency of O_3 until the natural frequency of O_3 (i. e. the frequency at which it 25 would oscillate with no A. C. voltage on its grid) exceeds the differential of 5 or 6 semitones in either direction. This presents a marked distinction between the method of three-electrode and two-electrode tubes. In order to couple a plurality of two-electrode tubes, the voltage from each tube must be impressed on all of the remaining tubes, so that a tendency for any single oscillator to shift in pitch will cause the rest of the coupled tubes to shift in pitch. Of course, this 30 shift will be smaller with coupling than without, nevertheless there will be some shift. With three-electrode tubes, on the other hand, each oscillator influences only the tube an octave below it, so that if the top master oscillator is of constant 35 frequency, all of the remaining tubes will exhibit constant frequency. In Fig. 1, for example, O_3 cannot affect the pitch of O_2 , and if the grid of a third oscillator were coupled to O_3 it could not affect the pitch of O_2 , nor of O_3 , and so forth. 40 45

However, an even more important distinction is the absence of the coupling voltage in the outputs of the various generators. For example, in Fig. 1, although O_2 oscillates at 400 cycles and O_3 at 200, the voltage output of O_3 contains no 50 trace of the additional 400 cycle coupling voltage. This is due to the unique characteristic of a three-electrode glow tube, the failure of the grid to affect the plate current once the discharge has been initiated. In Fig. 1, because O_3 has a 55

400 cycle voltage on its grid, the grid will go slightly positive twice in every cycle of the discharge current (200 cycles). On one of these two occasions, it will trigger the discharge, whereas, 5 on the other, it will have no influence on the plate current. Thus each oscillator will generate a rich tone of the correct fundamental frequency and all will be dependent on the top master oscillator.

- 10 Fig. 2 shows an arrangement of three tubes, using as a top master oscillator O_1 , the grid coupled inductive glow discharge oscillator as described in my previous application, Serial #46,449, series of 1935, which, as was pointed out, possesses 10 extreme stability. The lower generators, O_2 and O_3 , are simple relaxation oscillators and hence require no inductances. With O_1 oscillating, a voltage of frequency 2093 (corresponding to high C) is developed on resistor R_1 , and by means of 15 the connection RC , this voltage is impressed on the grid of oscillator O_2 . This causes oscillator O_2 to pull into step at 1046.5 cycles (corresponding to the next octave below) and a voltage of that frequency is developed across R_2 . This is 20 then impressed on the grid of O_3 causing it to oscillate at 523.3 cycles and a voltage of that frequency is developed on R_3 . The circuit diagram shows only three oscillators, but as many as desired could be used. For a complete organ there 25 would be 6 or 7 octaves, therefore each master oscillator would control 5 or 6 other tubes, and since there are 12 notes in an octave, 12 master oscillators would be required and 60 to 72 relaxation oscillators.

- 30 As indicated in Figure 2, the leads L_1 , L_2 and L_3 can be connected through decoupling resistors R_s to switches S , which in turn are connected through resistors R_s to transformers T_1 and T_2 . In the apparatus labeled T. C. various tone colors 35 and timbres can be imparted to the notes, which may then be amplified in A and transferred into sound by the loudspeaker L. S. The tone color device T. C. #1 is used to accentuate the high harmonics to give string and reed quality to the 40 notes, and the device T. C. #2 is used to filter out the high harmonics to give a pure, flute-toned quality. Without the resistances R_s and with only T. C. #2 in operation, the high frequency note on L_1 would be attenuated more than the low frequency note on L_3 because the filter device 45 T. C. #2 suppresses the high frequencies. In the same way, without R_s and with only T. C. #1 in operation, the high frequency note on L_1 would have a much greater intensity than the low note on L_3 . By proper selection of R_s and the primary 50 impedances of T_1 and T_2 , the notes all over the scale can be equalized in intensity, whether flute quality or rich quality is played. By making R_s large in comparison with R_1 , R_2 , R_3 and the primary 55 impedances T_1 and T_2 , the playing of several notes simultaneously will not affect the pitch or intensity of any single note.

- 60 Switch S_1 permits the application of a pitch or frequency vibrato to the issuing notes. The generator G supplies an alternating voltage of 4 to 6 cycles per second and thus periodically varies the grid bias of the master oscillator. A sufficient voltage swing can change the pitch of the master oscillator enough to produce a pleasing vibrato, 65 and since the master oscillator has complete control over the frequencies of the remaining oscillators, a vibrato is produced on all notes.

- 70 Fig. 3 shows a type of filter which is very effective in producing a flute quality tone from an oscillation which is rich in harmonics. This filter

would correspond to T. C. #2 in Fig. 2. The oscillations are fed in at I and taken out at O. The condensers C form low impedance paths to the high frequency notes and the signal at O is very free from harmonics. Such an arrangement would discriminate against those tones of high fundamental frequency, but as explained before, an arrangement as shown in Fig. 2, where the resistors R_s cut down the intensities of the low notes before they reach T. C. #2, produces 10 final signals of approximately equal intensity throughout the scale. Although such a filter system is not novel, it is believed that this method has not heretofore been applied to electrical musical instruments. Most filters in such instruments comprise inductances, which cause them 15 to discriminate against certain bands of frequencies.

The important improvements which I have herein set forth may thus be summarized:

First, a new method of controlling the frequency of several three-electrode glow tube oscillators in cascade, thereby preventing any fluctuations in succeeding tubes from affecting the preceding tube or tubes, and thereby yielding no 25 undesirable sub- or super-harmonics in the outputs of the individual generators.

Second, the use of a grid coupled inductive glow discharge oscillator in an electrical musical instrument as the topmost or master oscillator, 30 in conjunction with which the above mentioned control system produces a very rigid bank of oscillators.

Third, a method whereby the intensities of 35 notes of widely different tone color are equalized throughout the scale.

Although the grid coupled inductive glow discharge oscillator has been described in my previous application, Serial #46,449, series of 1935, its use in an electrical musical instrument as a 40 stable oscillator is herein set forth for the first time.

I claim:

1. In an electrical musical instrument, a plurality of electrical oscillation generators, each 45 of said generators comprising a gaseous glow discharge tube of a type having an anode, a cathode and a grid, and means for applying a voltage generated by one of said oscillation generators to the grid of a second of said oscillation generators, whereby to cause said second oscillation generator to oscillate at a frequency bearing a definite and fixed relationship to the frequency of the first mentioned oscillation generator.

2. In an electrical musical instrument, a plurality of electrical oscillation generators, each 55 comprising a gaseous glow discharge tube having an anode, a cathode and a grid, oscillation circuits for said oscillation generators, and means for impressing a voltage generated by one of said oscillation generators upon the grid of a second of said oscillation generators whereby to cause the last mentioned generator to oscillate at a frequency which is some harmonic fraction of the frequency of the first mentioned oscillation generator.

3. In an electrical musical instrument at least 60 three oscillation generators arranged in cascade, each of said generators comprising a gaseous glow discharge tube having an anode, a cathode and a grid, said oscillation generators having oscillation circuits, means for impressing a voltage generated by the first of said oscillation generators upon the grid of the second of said oscillation generators whereby to cause said second 65

70

75

oscillation generator to oscillate at a frequency which is some harmonic fraction of the frequency of said first oscillation generator, and means for impressing upon the grid of the third 5 of said oscillation generators a voltage generated by the second of said oscillation generators whereby to cause said third generator to oscillate at a frequency which is some harmonic fraction of the frequency of said second oscillation generator. 10
4. In an electrical musical instrument, a master oscillator or source of pulsating voltage, and a plurality of electrical oscillation generators, each comprising an oscillation circuit and a gaseous 15 glow discharge tube having an anode, a cathode and a grid, means for impressing the voltage produced by said master oscillator upon the grid of a second of said oscillators to cause the second oscillator to oscillate at a frequency which is 20 half the frequency of the master oscillator, means for impressing a voltage generated by said second oscillator, upon the grid of a third oscillator whereby to cause said third oscillator to oscillate at a frequency which is half the frequency of said 25 second oscillator and so on throughout the cascaded series.

5. The cascade of oscillation generators as claimed in claim 4, wherein said master oscillation generator comprises a gaseous glow discharge 30 tube having a feed circuit and a control circuit, the frequency of oscillation thereof being determined by both capacity and inductance in said control circuit.

6. The cascade of oscillation generators as 35 claimed in claim 4, in which said master oscillator comprises a gaseous glow discharge tube having an anode, a cathode and a grid, a feed circuit therefor and a control circuit therefor containing an inductance and a capacity by the combined 40 effect of which the frequency of said oscillator is stabilized, and means for energizing said grid

with a pulsating frequency derived from said control circuit.

7. In an electrical musical instrument, a plurality of master oscillation generators arranged to oscillate at frequencies related to each other as 5 the notes of the scale, in a high register, and, for each of said master oscillation generators a cascade of controlled generators, said last mentioned generators comprising each a gaseous glow discharge tube having an anode, a cathode and 10 a grid, and a semi-tuned controlled circuit, means for impressing a voltage generated by a master oscillator on the grid of an oscillator in its cascade, means for impressing a voltage generated by said last mentioned oscillator on a succeeding 15 oscillator and so on throughout each cascade whereby the generators in said cascades are caused to oscillate, each at a frequency which is half the frequency of the generator next highest in the cascade. 20

8. In an electrical musical instrument, a plurality of master oscillation generators arranged to oscillate at frequencies related to each other as the notes of the scale, in a high register, and, for each of said master oscillation generators a cascade of controlled generators, said last mentioned generators comprising each a gaseous glow discharge tube having an anode, a cathode and a grid, and a semi-tuned controlled circuit, means for impressing a voltage generated by a master 25 oscillator on the grid of an oscillator in its cascade, means for impressing a voltage generated by said last mentioned oscillator on a succeeding oscillator and so on throughout each cascade whereby the generators in said cascades are 30 caused to oscillate, each at a frequency which is half the frequency of the generator next highest in the cascade, and means for deriving from said oscillators portions of the voltage generated 35 therein for amplification and reproduction. 40
